UNITED STATES PATENT OFFICE.

WALTER EVELYN WRIGHT, OF HALIFAX, ENGLAND.

DRIVING BELT OR BAND.

1,209,241.

Specification of Letters Patent.

Patented Dec. 19, 1916.

Application filed August 11, 1915. Serial No. 44,991.

To all whom it may concern:

Be it known that I, WALTER EVELYN WRIGHT, residing at Halifax, in the county of York, England, have invented certain new and useful Improvements in or Relating to Driving Belts or Bands; and I do hereby declare the following to be a full, clear, and exact description of the invention, such as will enable others skilled in the art 10 to which it appertains to make and use the same.

This invention relates to driving belts or bands of the kind which are made or principally composed of canvas or other textile material or materials, which belts are peculiarly liable to fray at the edges owing to contact with the tines of the fork between which the belt or band runs. It has therefore been proposed to give such belts a complete edging of leather or the like material which is superior in wearing qualities to the material of which the belt is composed; and it has also been proposed to let into the 20 edges of the belt a piece of leather projecting beyond such edges so as to keep the textile part of the belt from contact with the forks. It is found, however, that such expedients detract from the utility of the belt. To overcome the disadvantages of the previous 25 constructions I now propose to insert a leather or other protecting strip into each edge of the belt, either at the back or on the front or driving surface of the belt, in such manner that the protecting strip forms a portion only of the thickness of the belt, and that the cross sectional shape of the belt is not altered.

According to this invention the belt or band is formed with a recess in either its inner or outer face at each edge thereof, into which recess is secured by riveting, metal stitching or other suitable means a strip of leather or other suitable material which exactly fills the recess, so that the belt or band 40 is of the same thickness and width throughout. The strips are preferably of rectangular cross section.

Copies of this patent may be obtained for five cents each, by addressing the "Commissioner of Patents, Washington, D. C."

The accompanying drawings show a portion of a belt constructed according to this invention.

Figure 1 is a perspective view. Fig. 2 is a side elevation on a larger scale and partly in section.

The reference numeral 1 indicates the canvas or other body of the belt, 2, 2 the strips 55 of leather, and 3 the metal stitches by which the strips are secured to the belt. Wire staples 4 may also be passed through the edge strips and into adjacent parts of the belt 1.

It will be observed that one face of the 60 belt is composed entirely of the textile material. The canvas body portion of the belt is formed of plies 5 arranged one above another and secured together in any approved way. The plies which form the back portion 65 of the belt are narrower than those which form the face or driving side of the belt, so that recesses 6 are formed at the edges of the rear face of the belt in which the strips 2 of wear-resisting material are 70 secured.

I claim as my invention:—

A driving belt having its main or body portion and its driving face formed wholly of textile material, said material being arranged in superposed plies certain of which are wider than others so that the belt is provided with longitudinal recesses at the edges of its rear face, and strips of wear-resisting material relatively stronger and 80 harder than the textile material secured in the said recesses and arranged flush with the edges and face of the main portion so that the normal sectional shape of the belt is preserved.

In testimony whereof I affix my signature in presence of two witnesses.

WALTER EVELYN WRIGHT.
